FLUID DISPENSING DEVICES

Richard W. Beall, Jr., Hermosa Beach, Calif.

Application October 6, 1953, Serial No. 384,376

11 Claims. (Cl. 222—484)

The present invention relates to the field of fluid dispensing devices, and more particularly to a combined stopper and fluid discharge unit that may be removably mounted in the mouth of a bottle.

The primary purpose in devising the present invention is to provide means by which alcoholic beverages in bottles are sealed from contact with the atmosphere at all times, except when the beverage is being dispensed.

In bars, cafes, and other establishments of this type, it is common practice to have numerous opened bottles of liquor displayed. The liquor so displaced is normally of high alcoholic content, and is dispensed from the particular bottle for which the customer calls through a normally open spout that extends downwardly through a stopper.

Dispensing of liquor from bottles in the above described manner has several objectionable features. One of these features is that alcohol is quite volatile, and over a period of time a considerable amount of liquor in a bottle may be lost due to evaporation that takes place through the pouring spout of the bottle. Another objectionable feature inherent to the normally open pouring spout is that it permits the alcohol in the liquor to absorb moisture from the atmosphere.

It will readily be apparent that the proof of liquor in a bottle having an open spout may change drastically over a period of time due to evaporation of alcohol and the absorption of water by the alcohol remaining in the bottle. Both the State and Federal Government have roving inspectors that may unexpectedly drop in and check the alcoholic content of liquors being dispensed by a bar, with the proof as printed on the labels of the bottles. Failure of the contents of a bottle of liquor to agree with the proof printed on the label thereof indicates adulteration of the liquor, and has been the reason for numerous bars being closed or having their licenses suspended. The fact that the adulteration or dilution of the liquor in a bottle occurred innocently due to the reasons above described is difficult to prove, and will not normally excuse a discrepancy between the actual alcoholic content in the liquor in a bottle and that printed on the label affixed to the bottle.

In an effort to remedy the above mentioned situation a variety of devices have been proposed that may be mounted on the mouth portion of a bottle to seal the contents of the bottle from contact with the atmosphere. However, the majority of these prior art devices were of cumbersome appearance, complicated in structure, and impeded the progress of a bartender when dispensing drinks. As a result of these defects, no one of the prior art bottle sealing devices has been used extensively for its intended purposes.

A major object of the present invention is to provide a stopper that may be removably mounted in the mouth of a bottle to effect an airtight seal, but one that has a spout mechanism associated therewith through which liquor from the bottle may be readily discharged by a simple manual operation.

2

Another object of the invention is to supply a combined stopper and fluid dispenser of simplified structure, one that may be fabricated from standard commercially available material, and due to its low cost of production 5 may be sold at a sufficiently attractive price as to encourage its wide-spread use.

A still further object of the invention is to furnish a combined stopper and fluid dispenser for a bottle that prevents alcohol containing fluids situated therein from 10 evaporating or becoming contaminated with alcohol absorbed from the atmosphere.

Other objects and details of the invention will be apparent from the following description, when read in connection with the accompanying drawings wherein:

Figure 1 is a side elevational view of the combined stopper and fluid dispenser disposed in the mouth of the bottle;

Figure 2 is a plan view of the device;

Figure 3 is a side elevational view of the device;

Figure 4 is a horizontal cross-sectional view of the device taken on the line 4—4 of Figure 3;

Figure 5 is a vertical cross-sectional view of the device taken on the line 5—5 of Figure 2;

Figure 6 is a horizontal cross-sectional view of the fluid dispensing spout taken on the line 6—6 of Figure 5;

Figure 7 is a vertical cross-sectional view of a portion of the actuating mechanism; and

Figure 8 is a vertical cross-sectional view of an alternate form of my invention.

Referring now to Figures 1, 3 and 5 for the general arrangement of the invention, it will be seen that it includes a resilient stopper S that may be deformed the desired amount to provide a fluid-tight seal when disposed in the mouth portion M of a bottle B. Stopper S is formed with a longitudinally extending bore A through which a tubular member T extends, which member terminates on its upper end in a spout C. A spring-loaded vertically movable air vent V extends downwardly through tubular member T to the confines of bottle B.

Air vent V, due to the spring-loading thereof, normally has the upwardly disposed entrance N thereto sealed by it engaging a seat E. An annular sealing member F mounted on air vent V normally seats in the lower entrance into tubular member T.

The invention is provided with three equally spaced, radially disposed claws J, which may be moved to removably engage a bead K formed on bottle B by rotation of a headpiece L. Rotation of headpiece L causes the claws J to grip bead K and the stopper S to be concurrently expanded to effect an air and fluid-tight seal with the interior surface of mouth portion M as will hereinafter be explained in detail.

Stopper S is formed from a resilient material such as rubber, and in the non-deformed condition has downwardly and inwardly tapered side walls 10. An annular plate 11 formed with a centrally disposed opening 12 is provided, which opening develops into a short upwardly extending tubular boss 13. The boss 13 has threads 13a formed on the interior thereof.

Plate 11 abuts against the lower surface 10a of stopper S, with the boss 13 projecting upwardly in bore A. Tubular member T is held in an upwardly extending position within the confines of bore A by threads 14 formed on the exterior surface of the member engaging the threads 13a of the boss as may best be seen in Figure 5.

A second annular plate 15 is provided that seats on the upper surface 10b of stopper S. Plate 15 is formed with a centrally located opening 16 through which tubular member T passes. The plate 15 as shown in Figure 4 has three equidistantly located sets of guide pins 17 and 17a extending upwardly from the top surface thereof. The pins 17 and 17a forming each set are circumferen-

tially spaced from one another a sufficient distance to slidably engage an elongated strip 18. Each of the strips 18 forms a part of one of the bead engaging claws J. In Figures 3 and 4 it will be seen that the outer end portion of each strip 18 is bent downwardly to form a bead engaging portion 18a.

Each strip 18 has an elongated transversely disposed slot 19 formed on the inwardly disposed portion thereof. Each slot has an enlarged slightly inwardly extending end portion 19a the purpose of which will later be explained.

In Figure 5 it will be seen that an internally tapped collar 20 is threaded on the upper portion of tubular member T. A horizontally disposed rod 21 of relatively short length extends outwardly from collar 20 and slidably engages a vertically curved groove 21a. The grooved 21a is formed on the interior surface of a bore 21b that extends downwardly through the central portion of headpiece L.

Three circumferentially spaced pins 22 extend downwardly from the under surface of headpiece L. Each of the pins 22 slidably engages one of the slots 19. Headpiece L may take a variety of forms, but a generally circular shape having a handle 23 forming a part thereof as shown in Figure 1 has been found quite satisfactory.

Upon the headpiece L being pivoted in a counterclockwise direction, the pins 22 slidably move in slots 19 to draw claws J inwardly until the inwardly disposed edges of strip 18 occupy the positions shown in phantom line in Figure 4. The strips 18 when in the inwardly disposed positions have the end portions 18a thereof gripping the bead K of bottle B. As the strips 18 assume their most inwardly disposed positions, the pins 22 move into the slot portions 19a. Pins 22a are removably locked in slot portions 19a due to the slight inwardly extending positions thereof, and will not be displaced therefrom until pressure is exerted on handle 23. Thus, the possibility of the claws J being inadvertently displaced from a bead gripping position is eliminated.

As the headpiece L is rotated the rod 21 is slidably moved in groove 21a. This movement of rod 21 in the vertically curved groove results in downward pressure being applied to plate 15 through the pins 22. Plate 15 as pressure is applied thereto is forced downwardly, with stopper S being compressed between plates 11 and 15. The stopper S as pressure is applied to the ends thereof deforms, and changes from the shape shown in Figure 3 to that illustrated in Figure 5. When the stopper S is disposed in the mouth portion M of a bottle B, the radial deformation of the stopper by application of pressure thereto as above described assures a fluid and airtight seal between the contacting surfaces of the stopper and bottle mouth portion. Thus, rotation of headpiece L serves a dual function, that of moving claws J to a bead engaging position, and expanding the stopper S to completely seal the mouth M of the bottle.

The spout C is angularly disposed relative to the tubular member T, with a horizontal platform 30 being formed at their junction. Airvent V includes a rigid tube 31 of relatively small internal diameter which extends downwardly through the tubular member T. An upwardly disposed portion of tube 31 projects through and is slidably supported in a vertical bore 32 formed in the platform 30. Tube 31 has a horizontal disposed trigger 33 mounted thereon. The trigger has a vertically disposed bore 34 formed therein in which the extremity of tube 31 is inserted. A counterbore serves as the entrance N to airvent V. An outwardly extending stop 35 is affixed to spout C, and is located directly above trigger 33. A compressed helical spring 36 encircles the portion of tube 31 above the platform. The spring 36 as it tends to expand exerts a force against the upper surface of platform 30 and the lower portion of trigger 33 to at all times urge the tube entrance N into airtight contact with seat E. The seat E as may best be seen in Figure 5 extends downwardly from the main body portion of stop 35.

In Figure 5 it will be noted that a guide 37 in the form of a ring is rigidly affixed to tube 31. The guide ring 37 is of such diameter as to be slidable within the confines of tubular member T. Guide ring 37 maintains airvent V in a fixed spacing relative to the interior surface of tubular member T, but does not appreciably obstruct the flow of fluid through the member.

The annular sealing member F is rigidly mounted on airvent tube A, and is so vertically disposed thereon that movement of the airvent tube results in the entrance 40 to tubular member T being either open or blocked by the sealing member. It will be particularly noted in Figure 5 that airvent tube A is at all times urged upwardly by spring 36, with the result that entrance E and 40 are only open when pressure is exerted downwardly on trigger 33.

The use and operation of the invention is extremely simple. The device as shown in Figure 3 is placed in the mouth portion M of a bottle B as illustrated in Figure 1 and the handle 23 then pivoted in a counterclockwise direction as far as possible. As pivotal movement of the handle 23 takes place, the headpiece L is rotated, with the stopper S being radially expanded to effect a fluidtight seal with the interior surface of mouth portion M, and 25 the claws J being drawn inwardly to grip bead K. The invention is now rigidly but removably affixed to the bottle B. It will be apparent that no fluid can escape from the bottle B when the invention is thus mounted thereon, nor can moisture be withdrawn from the atmosphere by the action of the fluid in the bottle, for the 30 spring 36 at all times maintains member F and seat E in sealing positions.

Upon the trigger 33 being moved downwardly by application of pressure thereto, the airvent tube 31 is likewise moved downwardly. Downward movement of the airvent tube separates seat E and sealing member F from entrances to tube 31 and tubular member T respectively. When the bottle B is mounted and trigger 33 has pressure applied thereto as above mentioned fluid 40 may flow freely from spout C, with air entering the bottle through vent V to replace the space previously occupied by the dispensed fluid all air enters bottle B for pressure equalizing purposes through an airvent V, with the result that fluid is dispensed from spout C without bubbling or gurgling. Upon pressure being removed 45 from trigger 33, the spring 36 immediately moves tube 31 inwardly to cause entrances N and 40 to be sealed by seat E and member F respectively.

An alternate form of my invention is shown in Figure 8. 50 This dispenser may be used on liquor bottles, and also mounted in the mouth of any bottle or container to maintain the contents thereof out of atmospheric contact except when fluid is dispensed therefrom. This alternate form of my invention is shown mounted in the mouth portion 100 of a bottle 101, but it should be clearly understood that the application of the preferred form or the alternate form of my invention is not limited to this particular type of fluid dispensing device.

Referring to the drawings, it will be seen that the 55 alternate form of fluid dispenser includes a tubular body 102 having a primary tubular pouring spout 103 extending downwardly through a centrally disposed bore 104 formed in a frusto-conical stopper 105. The stopper may be formed from cork, rubber, or other resilient material 60 not adversely affected by fluid contained in the bottle with which it is associated. At an intermediately located junction 106, the primary pouring spout 103 branches into an upwardly extending tubular member 107 and an angularly disposed secondary pouring spout 108. The upper end 65 of tubular member 107 is closed by a plate 109 from which a centrally disposed stem 110 depends. Stem 110 supports an annular packer 111 on the lower end thereof.

The portion of tubular member 107 directly above junction 106 is sealed by a plug 112 in which a longitudinally 70 extending bore 113 is formed. An elongate air tube 114

is mounted in bore 113 and is vertically slidable therein. Stem 110 projects downwardly into tube 114 and maintains packer 111 in slidable sealing contact with the interior surface thereof. A collar 115 is mounted on the upper portion of tube 114, which collar is disposed within the confines of tubular member 107 and in slidable contact with the interior wall surface thereof. A handle 116 projects from collar 115 and passes through a vertical slot 117 formed in tubular member 107. Handle 116 may take a variety of shapes, but I prefer that of a generally L-shape as shown in Figure 8. This L-shaped handle includes a stem 118 which supports a concave pressure plate 118a at its lower end, which plate may be of any desired shape.

A helical spring 120 that is constantly in compression is disposed within tubular member 107. The upper end of spring 120 contacts the lower face of collar 115, and the lower end of the spring bears against a packing washer 121 positioned on the upper surface of plug 112.

In Figure 8 it will be seen that an annular valve member 122 is provided which has a bore 123 extending therethrough to permit mounting thereof on the lower extremity of tube 114. Valve member 122 is at all times urged upwardly due to the compression on spring 120, and seats in fluid-sealing contact with the lower edge 122a of tube 114 as shown in solid line. A first air vent 124 is formed in tube 114 and so located that when my invention is in a non-dispensing position the vent may be seen above packer 111. A second air vent 125 is formed in the lower portion of tube 114 situated above valve member 122. A plug 126 or other conventional sealing means closes the lower end of tube 114. A flange 127 projects from primary spout 103 which limits the distance the spout may move downwardly relative to stopper 105. Flange 127 is also of assistance in forcing the stopper 105 downwardly into the mouth 100 of the bottle or container with which my invention is associated.

The operation of my invention is extremely simple. When it is desired to dispense fluid from a container on which my invention is mounted, the container is inverted and the handle 116 moved downwardly. Downward movement of the handle causes tube 114 to move relative to packer 111 whereby the air vent 124 is moved from the position shown in solid line to that indicated in phantom line. Downward movement of tube 114 also breaks the fluid sealing contact between member 122 and seat 122a by causing member 122 to assume the position shown in phantom line (Figure 8).

Fluid may then flow into the primary spout 103 from where it is directed into the secondary spout 108. A constant air pressure is maintained within bottle 101 due to the fact that air is immediately substituted for fluid as discharged. When fluid is discharged from the bottle 101, air enters tube 114 through air vent 124, and flows through tube 114 to enter the bottle through air vent 125. After the desired amount of fluid has been discharged from bottle 101, pressure is released from handle plate 118a, and compressed spring 120 returns tube 114 to the position shown where valve member 122 is in fluid-sealing engagement with seat 122a and vents 124 and 125 do not communicate. In practice it has been found desirable to have the internal diameter of secondary spout 108 somewhat less than the internal diameter of the primary spout 103 as this positively assures filling of the secondary spout with fluid and there is no tendency for air to pass upwardly therethrough.

Although the invention herein shown and described as fully capable of achieving the objects and providing the advantages hereinbefore mentioned, it is to be understood that is merely one embodiment of the invention, and that there is no intention to be limited to the details of construction thereof other than as defined in the appended claims.

I claim:

1. A combined stopper and fluid dispenser capable of being removably mounted in the mouth portion of a bottle that is formed with an outwardly extending bead which includes: a deformable stopper that may be inserted in the mouth portion of a bottle; a plurality of radially movable claws mounted on said stopper; means to concurrently deform said stopper for it to engage the interior surface of said mouth portion with a fluid tight seal and to move said claws inwardly for them to grip said bead to prevent inadvertent displacement of said stopper from said mouth portion; a tubular member extending longitudinally through said stopper; a pouring spout extending outwardly from the upper end of said tubular member; a vertically movable air vent extending downwardly through said tubular member; a sealing member mounted on said air vent, with said sealing member capable of sealing the lower entrance to said tubular member when in contact therewith; a stop extending outwardly from said spout above said air vent, said stop formed with a seat that seals the upper entrance to said air vent when said entrance is in contact therewith; spring means that at all times urge said air vent upwardly until further movement is restricted by said stop, with said air vent in its uppermost position having said upper entrance thereto sealed by said seat, and said sealing member blocking said lower entrance to said tubular member; and means to move said air vent downwardly whereby said entrances to said air vent and tubular member are unobstructed and fluid may be dispensed from said bottle through said tubular member and spout and air may enter said air vent through the upwardly disposed entrance thereof to equalize the air pressure on the interior of said bottle with the outside atmosphere.

2. A combined stopper and fluid dispenser capable of being removably mounted in the mouth portion of a bottle that is formed with an outwardly extending bead which includes: a deformable stopper that may be inserted in the mouth portion of a bottle; a plurality of radially movable claws mounted on said stopper; rotatable means which when actuated deform said stopper to effect a fluid tight seal with the interior surface of said bottle portion and retract said claws to grip said bead; a tubular member extending longitudinally through said stopper; a pouring spout extending outwardly from the upper end of said tubular member; a vertically movable air vent extending downwardly through said tubular member; spring means that at all times urge said air vent upwardly; means that seal the upper entrance to said air vent and the lower entrance to said tubular member when said air vent occupies a maximum upward position; and means to move said air vent downwardly whereby said entrances to said air vent and tubular member are unobstructed and fluid may be dispensed from said bottle through said tubular member and spout and air may enter said air vent through the upwardly disposed entrance thereof to equalize the air pressure on the interior of said bottle with the outside atmosphere.

3. A combined stopper and fluid dispenser capable of being removably mounted in the mouth portion of a bottle that is formed with an outwardly extending bead which includes: a deformable stopper that may be inserted in the mouth portion of a bottle; a plurality of radially movable claws mounted on said stopper; movable means which when actuated concurrently deform said stopper to effect a fluid tight seal with said mouth portion and move said claws into engaging positions with the bead on said mouth portion; a tubular fluid dispensing member extending downwardly through said stopper; a vertically movable air vent extending downwardly through said tubular member; spring means that at all times urge said air vent upwardly; means that limit the upward movement of said air vent; means that seal the upper entrance to said air vent and the lower entrance to said tubular member when said air vent occupies a maximum upward position; and, means to move said air vent downwardly whereby said entrances are unobstructed and fluid may be dispensed

75

from said bottle through said tubular member and air may flow into said bottle through said air vent.

4. A combined stopper and fluid dispenser capable of being removably mounted in the mouth portion of a bottle that is formed with an outwardly extending bead which includes: a deformable stopper that may be inserted in the mouth portion of a bottle; a plurality of radially movable claws mounted on said stopper; a rotatable means which when actuated move downwardly to deform said stopper to effect a fluid tight seal with the interior surface of said mouth portion and concurrently move said claws inwardly into engagement with the bead on said mouth portion; a tubular fluid dispensing member extending downwardly through said stopper; a vertically movable air vent extending downwardly through said tubular member; spring means that at all times urge said air vent upwardly; means that limit the upward movement of said air vent; a sealing member mounted on said air vent, with said sealing member capable of sealing the lower entrance to said tubular member when in contact therewith; and means to move said air vent downwardly whereby fluid may be dispensed from said bottle through said tubular member and air may flow into said bottle through said air vent.

5. A stopper for supporting a tubular fluid dispensing member and capable of being removably mounted in the mouth portion of a bottle that is formed with a circumferential outwardly extending bead which includes: a generally cylindrically shaped stopper formed of a deformable material, said stopper having a longitudinally extending bore formed therein; first and second annular plates abutting against the ends of said stopper, said plates formed with openings that are in alignment with said bore; a plurality of elongated claws slidably mounted on the upper surface of said second plate; means on said second plate that radially guide said claws; a tubular fluid dispensing member affixed to said first plate and in alignment with said opening formed therein, said member extending upwardly through said bore and opening in said second plate; a collar mounted on said tubular member, and disposed above said second plate; a horizontally disposed rod extending outwardly from said collar; a head piece formed with centrally disposed bore through which said tubular member extends and in which said collar is disposed, said head piece having a vertically curved groove formed on the surface of said bore formed therein, said groove being slidably engaged by said rod; a plurality of vertically disposed pins extending downwardly from said head piece, with each of said pins slidably engaging and inwardly extending curved slot formed in the inwardly disposed portion of one of said claws; and handle means to rotate said head-piece whereby the movement of said rod in said groove causes downward movement of said head-piece and second plate to compress said stopper and cause it to deform outwardly to engage the interior surface of said mouth portion with a fluid-tight seal and to concurrently draw said claws inwardly to engage said bead.

6. A stopper for supporting a tubular fluid dispensing member and capable of being removably mounted in the mouth portion of a bottle that is formed with a circumferential outwardly extending bead which includes: a generally cylindrically shaped stopper formed of a deformable material, said stopper having a longitudinally extending bore formed therein; first and second annular plates abutting against the ends of said stopper, said plates formed with openings that are in alignment with said bore; a plurality of elongated claws slidably mounted on the upper surface of said second plate; means on said second plate that radially guide said claws; a tubular fluid dispensing member affixed to said first plate and in alignment with said opening formed therein, said member extending upwardly through said bore and opening in said plate; a head-piece formed with a centrally disposed bore through which said tubular member extends,

said head-piece disposed above said second plate and parallel thereto; handle means for rotating said head-piece; and means actuated by the rotation of said head-piece that cause said stopper to be compressed and deform outwardly to engage the interior surface of said mouth portion with a fluid-tight seal and to concurrently draw said claws inwardly to engage said bead.

7. A combined stopper and fluid dispenser capable of being removably mounted in the mouth portion of a bottle which includes: a cylindrically shaped stopper that may be inserted in the mouth portion of a bottle; a tubular member extending longitudinally through said stopper; a pouring spout extending outwardly from the upper end of said tubular member; a vertically movable air vent extending downwardly through said tubular member; a sealing member mounted on said air vent, with said sealing member capable of sealing the lower entrance to said tubular member when in contact therewith; a stop extending outwardly from said spout above said air vent, said stop formed with a seat that seals the upper entrance to said air vent when said entrance is in contact therewith; spring means that at all times urge said air vent upwardly until further movement is restricted by said stop, with said air vent in its uppermost position having said upper entrance thereto sealed by said seat, and said sealing member blocking said lower entrance to said tubular member; and means to move said air vent downwardly whereby said entrances to said air vent and tubular member are unobstructed and fluid may be dispensed from said bottle through said tubular member and spout and air may enter said air vent through the upwardly disposed entrance thereof to equalize the air pressure on the interior of said bottle with the outside atmosphere.

8. A combined stopper and fluid dispenser capable of being removably mounted in the mouth portion of a bottle which includes: a cylindrically shaped stopper that may be inserted in the mouth portion of a bottle; a tubular member extending longitudinally through said stopper and rigidly affixed thereto; a pouring spout extending outwardly from the upper end of said tubular member; an independently movable air vent extending downwardly through said tubular member; spring means that at all times urge said air vent upwardly; means that seal the upper entrance to said air vent and the lower entrance to said tubular member when said air vent occupies a maximum upward position, and means to move said air vent downwardly whereby said entrances to said air vent and tubular member are unobstructed and fluid may be dispensed from said bottle through said tubular member and spout and air may enter said air vent through the upwardly disposed entrance thereof to equalize the air pressure on the interior of said bottle with the outside atmosphere.

9. A fluid dispenser which includes: a cylindrical stopper that may be inserted in the mouth portion of a bottle; a tubular spout through which fluid may flow from said bottle, which spout extends through said stopper and is rigidly affixed thereto; an independently movable air tube disposed within the confines of said spout; a valve member mounted on said air tube adapted to seat in fluid-sealing contact on the lower edge portion of said spout; means to admit air into said air tube when said valve member is in non-sealing contact with said spout; spring means that at all times urge said air tube upwardly to maintain said valve member in said fluid-sealing position; and means to move said air tube downwardly and unseat said valve member, permitting air to enter said tube whereby fluid may be discharged through said spout when said container is disposed in an inverted position.

10. A tubular fluid dispenser adapted to be held in the mouth portion of a container by a stopper that engages said mouth which includes: a primary tubular spout that may be disposed in a bore formed in said stopper; an angularly disposed secondary spout in fluid communication with said primary spout; a tubular member extending up-

wardly from said primary spout; a plug disposed in said tubular member having a bore extending longitudinally therethrough; an air tube having a lower sealed end that is longitudinally disposed in said primary spout and tubular member, and slidably supported in said bore; a collar mounted on the upper end of said air tube; a handle affixed to said collar and projecting through a vertical slot formed in said tubular member; a valve member mounted on the lower portion of said air tube capable of seating in fluid-sealing contact with the edge of said primary spout projecting within said container; spring means that at all times urge said air tube upwardly to maintain said valve member in said fluid-sealing contact with said primary spout; a plate closing the upper end of said tubular member; a stem depending downwardly from said plate into said air tube; and a packer mounted on said stem in slideable sealing contact with the interior surface of said air tube, and normally disposed below a first air vent formed in said tube, but when said air tube is moved downwardly to unseat said valve member, said first air vent moving to a position below said packer and above the upper surface of said plug to permit air to enter said air tube from the exterior thereof and flow through said tube to enter said container from a second air vent formed in said tube.

11. A tubular fluid dispenser capable of being held in the mouth portion of a container by a stopper that engages said mouth which includes: a tubular spout that may be disposed in a bore formed in said stopper having a fluid discharge opening formed therein; a tubular member that extends upwardly from said spout, the upper end of which is closed; a plug disposed in said tubular member which has a bore extending longitudinally therethrough; an air tube, the lower sealed end of which is longitudinally disposed in said spout and tubular mem- 35

ber and slidably supported in said bore; a handle affixed to said air tube extending outwardly through a vertical slot formed in said tubular member; a valve member mounted on the lower portion of said air tube capable of seating in fluid-sealing contact with the edge of said spout projecting within said container; spring means that at all times urge said air tube upwardly to maintain said valve member in said fluid-sealing contact with said spout; a stem affixed to said tubular member and extending downwardly into said air tube; and a packer mounted on said stem in slideable sealing contact with the interior surface of said air tube, and normally disposed below a first air vent formed in said tube, but when said air tube is moved downwardly to unseat said valve member, said first air vent moving to a position below said packer and above the upper surface of said plug to permit entry of air to said air tube from the exterior and flow therethrough to enter said container through a second air vent formed in said tube.
